UNITED STATES PATENT OFFICE.

HARRY C. HEATH, OF SAN FRANCISCO, CALIFORNIA, ASSIGNOR TO HOUSEHOLD NECESSITY COMPANY, OF SAN FRANCISCO, CALIFORNIA, A CORPORATION OF CALIFORNIA.

WASHING APPARATUS.

Application filed January 25, 1924. Serial No. 688,436.

This invention relates to washing machines and more particularly to an improved machine constructed as a unit, and adapted for insertion in stationary wash tubs or the like.

This invention consists broadly of a stand pipe or column having a blower and motor incased at its upper end, and a perforated housing at its lower end, an inlet for the blower positioned within the stationary tub, the said blower adapted to draw hot air from the tub, force it through the stand pipe and out through the perforations of the housing into the contents of said tub and continuously circulate the air in this manner to agitate the water thereby forcing the same through the contents of the tub.

Air is forced by the blower at considerable pressure and is emitted from the housing perforations and evenly distributed through the contents of the tub and the water therein is agitated to a considerable extent which causes an undulating movement within said tub and the frictional contact of the air combined with this movement of the water thoroughly cleanses the contents of the tub.

Washing machines of the present type are all more or less dependent upon agitation of the machine itself causing frictional contact with the contents thereof, or agitation of the contents against corrugations within the tub which in either case causes more or less wear and tear upon the articles therein, and it is the primary object of this invention to eliminate these objectionable features.

The principal object of this invention is to construct a washing machine adapted to force a column of air through the contents of the tub to cleanse the same by continued circulation of air and water through the fabric thereof at considerable force.

Another object is to construct a washing machine as a unit adapted for insertion in any stationary tub or like container.

Another object is to produce a washing machine constructed in accordance with this invention, which is simple in construction, positive in operation, and requires a minimum power supply in its operation.

Other objects and features of this inven-

tion will appear with reference to the subjoined specification and the accompanying two sheets of drawings, in which:

Figure 1 is a plan view of a stationary tub of the ordinary type showing my washing machine in place in one section thereof.

Figure 2 is an enlarged elevation of the machine shown in Figure 1, taken on line 2-2 looking in the direction of the arrows, a portion of the tub being shown in section.

Figure 3 is an axial section taken on line 3-3 of Figure 5, looking in the direction of the arrows, the motor casing and control switch thereof being shown in elevation.

Figure 4 is a transverse section taken through the stationary tub on line 4-4 of Figure 1 looking in the direction of the arrows, a portion of the stand pipe and housing of the machine being shown in section.

Figure 5 is a plan view, parts being broken away from clearness of illustration.

Figure 6 is a plan view of the blower disc, a portion of the motor spindle being shown in section and the vanes of the blower in dotted lines.

Referring more particularly to the drawings; 10 designates an ordinary type of stationary tub construction, preferably constructed with two sections 11 and 12, one for washing and the other for rinsing purposes. My improved washing machine is shown inserted in one of these sections as 11 and clamped in place to partition 13 thereof, as clearly shown in Figures 1 and 3, or to the rear wall of the tub as shown in Figure 4 if desired.

My washing machine proper comprises, a rectangular air distributor housing 14, preferably of non-corrosive material such as aluminum for example, the bottom closure therefor being a separate cast plate 15 secured to said housing by screws 16. A split clamping sleeve 17 as particularly shown in Figure 2, is cast integral with the housing 14 and extends upwardly therefrom at one corner and is slightly offset; said sleeve is provided with outwardly extending ears 18, and a clamp screw 19, adapted to clamp said sleeve tightly around a stand pipe 20 fitting within the sleeve and extending upwardly

above the upper edge of the partition 13 of the stationary tub.

A supporting clamp 21 encircles the stand pipe 20, and is adjustably secured thereto by a winged screw 22. A hook 23 is integrally formed with said clamp 21 and engages the upper edge of the partition 13 or the rear wall of the tub as shown in Figure 4 if preferable; said clamp serving to hold the housing 14 and stand pipe 20 in rigid upright position, as shown in Figure 3.

A blower housing 24 is supported upon the upper end of the stand pipe 20 by a neck member 25 cast integrally therewith and adapted to enclose said stand pipe, the lower end thereof is provided with a clamping sleeve 26 similar to the sleeve 17.

The blower housing 24 is preferably cast of non-corrosive material, such as aluminum and extends horizontally from the neck 25 and is provided with a circular chamber 27 having an axial extension 28 cast integral with the housing 24. An opening 29 is formed in the top wall 30 of the housing 24 and a motor casing 31 attached to said wall by screws or otherwise.

A spindle 32 see Figure 3, to which the motor armature is attached extends through the motor casing 31 into the chamber 27 and extension 28, said motor casing 31 and spindle 32 extending axially of the housing and said extension 28. A blower disc 33 is positioned within the housing 24 just below the opening 29 and is secured to the spindle 32 by a rigid collar 34 and set nut 35 screwed upon the lower end of said spindle 32.

Radially extending vanes 36 are formed on the under side of the blower disc 33 and extend from the peripheral edge of said plate disc inwardly and end near the spindle 32, as shown in Figure 3 and more particularly Figure 6.

The axial extension 28 forms the intake for the blower and preferably extends horizontally therefrom and ends in a goose-neck 37 extending parallel with the stand pipe 20.

The distributor housing 14 is provided with a series of spaced outlet perforations 38 communicating with the tub section 11 and adapted to deliver air thereto circulated from the blower 33.

A button switch 39 is attached to a bracket 40 formed on the motor casing 31 and the motor terminals extend therefrom and are attached to any source of energy, such as, an ordinary lamp socket (not shown).

Upon operation of the motor the blower is driven at high speed and draws hot air through the inlet pipe 37 and extension 28 and forces it out through chamber 27, stand pipe 20 and into the distributor housing 14, thence through the contents of the tub and is continuously circulated in this manner.

Best results are obtained by the circulation of hot air drawn from the tub, and

for this reason I provide the tub with a cover 41 as shown in Figures 2 and 4 adapted to retain the steam therein from the hot water in the tub. The cover 41 may be slotted out as at 42 to fit around the stand pipe 20 and inlet pipe 37. The air is forced from the blower at considerable pressure, and enters the water and contents of the tub, thereby agitating the water and contents to a considerable extent which causes an undulating motion within the tub as indicated in dot and dash lines in Figure 4. The clothes are agitated by this motion and the air forces the suds through the fabric thereof to such an extent that the cleansing operation is readily and completely accomplished.

The distributor housing 14 is provided with a series of angularly extending deflector ribs 43, as shown in dotted lines in Figure 1, said ribs are spaced apart and extend radially and outwardly away from the stand pipe opening. These ribs enclose the several rows of outlet openings 38 and serve to deflect and equally distribute the forced air from the blower to said outlet openings.

The tub is also provided with the ordinary drain connection 44, to drain the water therefrom, a fragmentary portion of which is shown in Figure 2, section 11, and in section 12 a plug 45 is shown for a similar drain connection not shown.

Having thus described my invention, and an embodiment of it, in the full, clear and exact terms required by law, and knowing that it comprises novel, useful and valuable improvements in the art to which it pertains, I here state that I do not wish to be limited to the precise construction and arrangement of the several parts, as herein set forth, as the same may be variously modified by a skilled mechanic without departing from the spirit and scope of my invention as defined in the appended claims.

What I claim and desire to secure by Letters Patent of the United States, is the following, to-wit:

1. A washing machine comprising, a stationary tub, a blower mounted upon said tub, a motor for operating said blower, an adjustable stand pipe for supporting said blower, an air distributor removably secured to said stand pipe, said distributor having a rectangular shape, fitting approximately the bottom of said tub, and provided with a plurality of outlets on one side thereof and deflecting ribs on the opposite side, said blower adapted to direct an air blast through said outlet of said distributor and said ribs causing the air to circulate within said tub.

2. A washing machine comprising, in combination, a tub, a blower having a housing, said housing being adjustably mounted above said tub, an air distributor connected to said housing, said air distributor adapted to cover approximately the entire bottom of

the tub, a motor above said housing for said blower, said blower adapted to cause the hot air to circulate in said tub.

3. A washing machine comprising in combination, a tub having a blower, a stand pipe for supporting said blower above said tub, an air distributer adjustably mounted upon said stand pipe and connected to said blower, said air distributer consisting of a hollow

rectangular casing having perforations and 10 deflecting ribs adapted to direct the air through said ribs and said perforations into said tub.

In testimony that I claim the foregoing, I have hereto set my hand this 29 day of 15 Dec., 1923.

HARRY C. HEATH.
